ELECTRONIC TEST EQUIPMENT CABINET

Nicholas De Wolf, 60 Pinckney St., and Alexander V. d'Arbeloff, 240 Marlboro St., both of Boston, Mass., and Nicholas J. Cedrone, 180 Bear Hill Road, Waltham, Mass.

Filed Sept. 4, 1962, Ser. No. 71,536

Term of patent 14 years

(Cl. D26—1)

FIG. 1

FIG. 2

FIG. 3

FIG. 1 is a front perspective view of an electronic test equipment cabinet showing our new design;

FIG. 2 is a reduced scale rear perspective view; and

FIG. 3 is a left side elevational view also on a reduced scale.

We claim:

The ornamental design for an electronic test equipment cabinet, as shown.
